UNITED STATES PATENT OFFICE.

FREDERICK F. GAINES, OF SAVANNAH, GEORGIA. ASSIGNOR, BY MESNE ASSIGNMENTS, TO AMERICAN ARCH COMPANY, OF NEW YORK, N. Y., A CORPORATION OF DELAWARE.

LOCOMOTIVE-BOILER.

1,138,059.

Specification of Letters Patent.

Patented May 4, 1915.

Application filed October 13, 1913. Serial No. 794,913.

To all whom it may concern:

Be it known that I, FREDERICK F. GAINES, a citizen of the United States, and a resident of Savannah, Chatham county, Georgia, have invented certain new and useful Improvements in Locomotive-Boilers, of which the following is a specification.

My invention relates to improvements in locomotives and has particular reference to improvements in the fire-boxes of locomotive boilers.

The object of my invention is to increase the efficiency and the fuel economy of locomotive boiler fire boxes; to provide a locomotive boiler fire box wherein the fire box gases shall be thoroughly intermingled and intermixed to the end that the fuel shall be efficiently consumed; wherein the progress of the gases from the fuel bed to the flues shall be baffled; wherein the temperature of the burning gases shall be maintained at a point of high efficiency; and wherein the hot gases of combustion shall be forced to travel over substantially the whole interior surface of the fire box.

A further object of my invention is to provide a construction of refractory cross wall or baffle wall for locomotive boilers of the extension fire box type; which shall be capable of being installed with a minimum of labor and expense.

A further object of my invention is to provide a construction of cross wall for such fire boxes through which air can be introduced to the fire box for mixing with the burning fire box gases above the fuel bed and without cutting or disturbing the fire box sheets.

A further object of my invention is to provide a locomotive boiler fire box of the extension fire box type with a refractory air feeding baffle wall of simple and durable construction.

My invention consists in a locomotive boiler fire box of the extension fire box type provided with a refractory cross-wall arranged at the forward end of the fire-box and supported upon the floor of the extension, having downwardly extending portions in the forward end of the fire box extending from the base of the cross wall to the level of the grate and in contact with the front water leg and provided with air conduits adapted to cause air to be in-

jected into the fire box beneath the arch and from beneath the grate.

My invention further consists in a fire box of the extension combustion chamber type, having a cross wall supported on the floor of the extension, adjacent to the rear end thereof, an extension of the wall projecting downwardly to the level of the grate, air conduits rising through the wall from the lower end thereof and opening through the rear face of the wall, water circulating tubes rising from the floor of the extension and extending upwardly and rearwardly through the fire box to the end thereof, and a refractory arch supported by the tubes and extending rearwardly through the fire box from the upper end of the said wall, said air conduits opening into the fire box beneath the arch.

My invention further consists in a locomotive fire box of the extension fire box type provided with a refractory cross wall arranged in the rear end of extension and having vertically extending air conduits opening through the rear face of the wall at their upper ends and connected at their lower ends with protected air feeding conduits arranged in the forward end of the fire box adapted to admit air into such vertical conduits from beneath the grate.

My invention also consists in the several arrangements of parts and in the features of construction whereby the above and other objects are attained, and all as hereinafter described, and particularly pointed out in the appended claims.

My invention will be more readily understood by reference to the accompanying drawings forming part of this specification and in which—

Figure 1 is a central, vertical, longitudinal section of a fire box equipped with a baffle wall and embodying my invention; Fig. 2 is a transverse vertical section of the fire box on the line 2—2 of Fig. 1; Fig. 3 is a transverse section of the arch on line 3—3 of Fig. 1; and Fig. 4 is a detail section of the forward end of the fire box showing a modified form of my invention.

Within the last few years the benefits of baffle walls in locomotive fire boxes have been amply demonstrated, and it has been the object of inventors to apply such baffle walls to substantially every construction of

locomotive boiler. In such application, many difficulties have arisen particularly as it is desired that air be added to the burning fire box gases above the fuel bed, and it has been a difficult problem to provide a wall in fire boxes of the extension combustion chamber type through which air could be admitted to the fire box above the fuel bed without cutting or otherwise mutilating the boiler sheets, particularly the sheets which form the lower part of the extension of the fire box.

By means of my present invention I am enabled to build cross walls in the fire boxes of the extension combustion chamber type, and thereby derive the benefits of such walls without the expense or the detrimental results of providing openings in the several sheets of the boiler through which air can be admitted to the wall, and further, I am enabled to install cross walls in such fire boxes with a minimum expenditure of time and labor.

A locomotive boiler fire box A, as illustrated in the drawings, comprises a flue sheet a^1 at its forward end, a rear sheet a^2 provided with a fuel door or opening a^3 , a crown sheet a^4 and side sheets a^5 . The fire box is provided with a grate a^6 of usual construction and the space occupied by the grate is less than the total length of the fire box and consequently the front water leg a^7 is arranged rearwardly from the flue sheet and the portion of the fire box a^8 which lies between the front water leg and the flue sheet forms the fire box extension or the extension combustion chamber.

The strong artificial drafts which it is necessary to use in locomotive boilers at the present time, in order that sufficient fuel may be consumed to produce the necessary power, results in the fire box gases being drawn directly from the fuel bed to the flues a^9 , which extend forwardly in the boiler 45 from the flue sheet a^1 . The object of a cross wall or baffle wall in the boiler, particularly when arranged in the front end thereof, is to prevent such direct flow of the gases of combustion and force them into the rear 50 part of the fire box before they flow forwardly into the flues, and this results in the gases flowing over substantially the whole interior surface of the fire box, and in position to best deliver their heat to the water 55 of the boiler.

The front water leg a^7 of the boiler is joined at its upper end to the main part of the boiler by means of a water space a^{10} directly below the floor a^{11} of the extension 60 portion of the fire box. I provide a refractory cross wall B in the extension of the fire box supporting it upon the floor a^{11} of the extension, and I preferably arrange it adjacent to the rear end or mouth of the extension. This wall is composed of several rows

b^1 of refractory bricks b^2 and rises to substantially half of the height of the fire box at this point. I provide this wall with several air conduits b^3 opening at their upper ends b^4 into the fire box through the rear face of the wall. I curve the lower ends of these conduits rearwardly to join small conduits b^5 rising from the lower part of the fire box and in contact with the wall b^6 of the front water leg a^7 . These lower conduits b^5 preferably consist of metal tubes b^7 which extend downwardly in contact with the rear face of the front water leg and project below the lower edge of the fire box, and I protect these tubes by means of refractory coverings b^8 which practically form downwardly extending projections of the wall B, which extensions project downwardly to substantially the level of the grate. I support these refractory coverings or conduits upon a transversely extending shelf b^9 secured by bolts b^{10} to the rear wall b^6 of the front water leg. The tubes or pipes b^5 are provided on their lower ends with forwardly curved elbows b^{11} having flaring inlets b^{12} , and I support these tubes and their elbows in position by means of brackets b^{13} , which I bolt to the mud ring a^{14} of the fire box. The air inlet conduits thus extend from their outlets b^4 to the inlets b^{12} of the several tubes and serve to inject air into the fire box above the fuel bed and from beneath the fire box. The wall B, as thus described, divides the fire box into a main combustion chamber a^{12} above the grate and the auxiliary combustion chamber a^8 between the wall and the flue sheet. Under some conditions in order to obtain the desired results, I arrange a refractory arch C extending rearwardly and upwardly through the fire box from the upper end of the wall B and for the purpose of supporting this arch in position I arrange water circulating tubes D extending longitudinally through the fire box which rise from the floor of the extension combustion chamber a^8 and curve upwardly and rearwardly therefrom, passing through the upper part of the wall B and then extending in an upwardly inclined position to the rear water leg a^{13} of the fire box. These tubes 110 D serve to increase the circulation of water from the lower to the upper part of the boiler, and as they extend through the hottest zone of the gases in the fire box they serve to increase the steaming capacity of 115 the boiler.

The arch C consists of several transverse rows c^1 of refractory bricks c^2 . These bricks I preferably make of such a length that they extend from tube to tube and are supported at their ends on adjacent tubes. This refers to the bricks which fill in the spaces between the tubes.

I arrange side bricks c^3 to fill in the spaces between the outermost tubes and the 130

- adjacent side sheets. These bricks c^3 rest at their inner ends upon the outer tubes and project upwardly and outwardly against the side sheets. They are wedgingly interposed between the outer tubes and the side sheets and are thus maintained in position. In some situations one or two of the rows c^1 are sufficient to provide an arch which produces the results desired, but the form illustrated in the drawings consists of a number of transverse rows c^1 , and the rear end of the arch is preferably arranged about the middle of the length of the fire box. The air conduits in the wall discharge the air beneath the arch in position where it is best intermingled and mixed with the rising fire box gases at the point where they are deflected rearwardly in the fire box by the arch.
- 20 In the form of my invention illustrated in Fig. 2, the air inlet pipes b^7 extend upwardly through the refractory tiles or coverings b^8 and end adjacent to the lower end of the wall and there connect with the air conduits b^8 of the wall B, but in the form shown in Fig. 4, the tiles b^8 themselves form part of the conduit, the pipes b^7 ending adjacent to their lower ends.
- The economical results attained are very great and it will now be clear that by means of my construction, I am enabled to provide cross walls in fire boxes of the extension fire box type without the necessity of cutting holes in the boiler sheets or providing air inlet tubes which pass through the boiler space a^7 below the fire box extension.
- This application is subsidiary to the application of John P. Neff, Serial No. 767,055, filed May 12, 1913, in which some of the things shown herein are claimed by Mr. Neff as the first inventor thereof.
- I claim:
1. In a locomotive boiler fire box of the extension fire box type, a refractory cross wall closing the lower part of the mouth of the extension, water circulating tubes rising from the floor of the extension and extending upwardly and rearwardly therefrom to the rear end of the fire box, a refractory arch composed of a plurality of fire brick supported on and by said tubes and extending upwardly and rearwardly through the fire box from the upper end of said wall, said wall being provided with air conduits extending from the lower end of the fire box in contact with the rear wall of the front water leg, and centrally through the wall and provided at their upper ends with discharge openings adapted to emit heated air from the rear face of the wall beneath the arch and above the fuel bed.
2. In a locomotive boiler fire box of the extension fire box type, a refractory cross wall closing the lower part of the mouth of the extension provided with vertically extending, transversely spaced air conduits, and having relatively narrow, hollow refractory portions extending downwardly to the level of the grate adapted to feed air to said conduits, a bracket secured to the rear wall of the front water leg of the boiler and supporting said downwardly extending portions, and air inlet pipes extending upwardly from the lower part of the fire box one for each conduit and feeding air to said hollow extensions of the wall, whereby air is admitted through the conduits to the fire box above the fuel bed.
- In testimony whereof, I have hereunto set my hand, this 1st day of Oct., 1913, in the presence of two subscribing witnesses.
- FREDERICK F. GAINES.
